RAILWAY SIGNALING SYSTEM

William F. Zane, La Grange, Ill., and George W. Baughman, Swissvale, Pa., assignors to The Union Switch and Signal Company, Swissvale, Pa., a corporation of Pennsylvania

Application July 18, 1941, Serial No. 402,906

4 Claims. (Cl. 246—33)

Our invention relates to a railway system adapted for use in track stretches where traffic moves in both directions over a single track.

It is an object of our invention to provide an improved signaling system in which the signals controlling both directions of traffic are governed by a single line circuit.

A further object of our invention is to provide an improved system of the type described which employs coded energy in the line circuits and which is arranged so that a cross between the line wires will not produce a false clear signal.

Another object of our invention is to provide an improved signaling system of the type described.

We shall describe two forms of railway signaling system embodying our invention, and shall then point out the novel features thereof in claims.

In the drawings,

Fig. 1 is a diagram consisting of Figs. 1A and 1B and showing a stretch of railway track equipped with one form of signaling system embodying our invention, and

Fig. 2 is a diagram consisting of Figs. 2A and 2B and showing a stretch of railway track equipped with a modified form of signaling system embodying our invention.

Similar reference characters refer to similar parts in both views.

Referring to Fig. 1 of the drawings, there is shown therein a stretch of single track railroad over which traffic moves in both directions. To facilitate description of the equipment it will be assumed that the right-hand end of the track stretch is east and that the left-hand end thereof is west.

The track stretch includes passing sidings which are located at appropriate intervals and permit traffic to be diverted from the main track under the customary control of switches. Two such passing sidings are shown and are designated X and Y.

The rails 1 and 2 of the track stretch are divided by insulated joints 3 into track sections designated 2T, 3T, 4T, 5T, etc. Each of the track sections is provided with a track circuit including a track battery connected across the section rails at one end of the section, and a track relay, designated TR with a suitable prefix, connected across the section rails at the other end of the section.

Eastbound traffic through the track stretch is governed by a plurality of trackway signals designated 4S, 6S and 8S, while westbound traffic

through the track stretch is governed by signals designated 1S, 5S and 3S. The signals shown are of the color light type, but it should be understood that the invention is not limited to the use of signals of this type and that any appropriate form of wayside signal well known in the art may be employed. Each of these signals has a green or clear lamp G, a yellow or caution lamp Y, and a red or stop lamp R. The signals 8S and 3S at the entrance ends of the passing sidings have upper portions which include the green, yellow and red lamps as illustrated in the drawings, while these signals may also have lower portions, not shown, governing movement of trains from the main track onto the passing sidings.

The diagram which forms the drawings shows the means for controlling the signals 4S, 5S, 6S and 7S. The means for controlling the signals 3S and 8S is not a part of this invention and has not been shown, and these signals may be controlled in any appropriate manner well known in the art.

In most cases the contacts associated with each relay are shown in the drawings directly under the relay winding. However, in a few instances the relay contacts are separated from the relay winding, and where this is done the relay with which the contact is associated is indicated by appropriate reference characters located directly above the contact.

In the system provided by this invention the signals 4S and 5S are controlled over a line circuit J which includes line wires 20 and 21, while signals 6S and 7S are controlled over a line circuit K which includes line wires 22 and 23.

Each signal location is provided with a suitable source of direct current such as a storage battery, not shown, the terminals of which are designated B and C.

The equipment is shown in the condition which it assumes when the track stretch is vacant. At this time the coding relay JCR is supplied with energy of 180 code frequency from a code transmitter 180CT over a circuit which includes front contact 25 of relay 3TR. This energy consists of 180 energy impulses a minute which are separated by periods of equal duration during which no energy is supplied.

When the coding relay JCR is picked up, its contacts 26 and 27 establish a circuit to supply impulses of "master" code energy to the line circuit J. At this time as sections 2T and 3T are vacant, relay 3D is picked up and terminal B of the source of direct current is connected

through front contact 28 of relay 3D and front contact 26 of coding relay JCR to line wire 20, while terminal C is connected through front contact 29 of relay 3D and front contact 27 of coding relay JCR to line wire 21 so that the "master" code supplied to line circuit J is of normal polarity.

This master code energy is supplied over the line circuit and through back contacts 30 and 31 of impulse relay JIR to line relays 5P and 5N.

The line relays 4P, 5P, 6P and 7P are of the stick polar type having contacts which are moved to their normal positions, as shown, on the supply of energy of normal relative polarity to the relay winding, and to their other or reverse positions on the supply of energy of reverse relative polarity to the relay winding. The contacts of these relays when moved to either position remain in that position until the relay winding is supplied with energy effective to move the relay contacts to their other position.

The line relays 4N, 5N, 6N and 7N are of the biased polar type and respond to flow of energy in the windings thereof in one direction only.

The polar line relays P control the connection from the line circuits to the line relays N so that if the contacts of the polar relays respond to changes in the polarity of the current supplied to the line circuits, the relays N will be connected with the line circuits in such manner that energy will flow in the relay windings in the direction effective to pick up the relay contacts.

The arrangement of the relays P and N is not a part of this invention and this feature is shown and claimed in an application for Letters Patent of the United States, Serial No. 194,160 of Harry E. Ashworth, filed March 5, 1938.

As "master" code energy of normal polarity is supplied to the line circuit J, the contacts of relay 5P are shifted to their left-hand position as shown, while energy from the line circuit is supplied to relay 5N and produces code following operation of the contact of this relay. Accordingly, the two portions of the primary winding of decoding transformer 5DT are alternately energized and energy is induced in the secondary winding of this transformer. The energy induced in one of these secondary windings is supplied through the resonant rectifier unit 5RU to the relay 5H. The unit RU is constructed in the manner well known in the art and is arranged so that it passes sufficient energy to pick up the relay 5H when and only when the relay 5N is responding to energy of 180 code frequency.

As contact 35 of relay 5H is picked up and as contact 36 of relay 5P is in its normal position, the circuit of the green lamp G of signal 5S is complete and this lamp is lighted so that the signal 5S provides its green or clear indication.

The energy induced in the other secondary winding of the transformer 5DT is supplied to the impulse relay JIR. The relay JIR is of a type which responds to energy of one polarity only and the various parts of the equipment are arranged so that energy of the polarity effective to pick up the contacts of the relay JIR is supplied to the relay on release of the contacts of relay 5N. Accordingly, during the supply of an impulse of "master" code the contacts of relay JIR are released, while during the "off" periods in the "master" code the contacts of relay JIR pick up to disconnect the line circuit from the relays 5P and 5N, and to establish a circuit to permit impulses of "feed-back" energy to be supplied to the line

circuit. The contacts of relay JIR when picked up remain picked up for a short time interval, but become released and reestablish the circuit of the relays 5P and 5N before the start of the next "on" period in the master code.

When the contacts of relay JIR are picked up, a circuit is established to supply an impulse of "feed-back" energy to the line circuit J. As sections 6T and 7T are unoccupied, the relay 6H is picked up so that the impulse of "feed-back" energy is of normal polarity.

At this time terminal B is connected through back contact 38 of relay 5SR, front contact 39 of relay 6TR, front contact 40 of relay 6H, and front contact 30 of relay JIR to line wire 20, while terminal C is connected through front contact 42 of relay 6H, and front contact 31 of relay JIR to line wire 21.

The impulses of "feed-back" energy are supplied over the back contacts 26 and 27 of relay JCR to line relays 4P and 4N so that the contacts of relay 4P occupy their normal positions, while the contacts of relay 4N pick up and release. One contact of relay 4N establishes circuits to alternately energize the two portions of the primary winding of transformer 4DT, while the other contact of the relay 4N rectifies the energy supplied from the secondary winding of transformer 4DT to relay 4H. As a result, contact 44 of relay 4H is picked up and establishes the circuit which includes normal polar contact 45 of relay 4P for supplying energy to the green lamp G of signal 4S so that this lamp is lighted and conditions signal 4S to provide its green or clear indication.

From the foregoing it will be seen that when the track stretch is vacant, "master" code energy of positive or normal polarity and 180 code frequency is supplied to the west end of the line circuit J and conditions signal 5S to provide its clear indication, while during the "off" periods of the "master" code impulses of "feed-back" energy of positive or normal polarity are supplied to the east end of the line circuit and condition signal 4S to provide its green or clear indication.

The equipment for controlling signals 6S and 7S operates in the same manner as that for controlling signals 4S and 5S, and as the track stretch is vacant, signals 6S and 7S are conditioned to provide their green or clear indications. At this time "master" code energy of 180 code frequency and normal polarity is supplied to the east end of line circuit K, while "feed-back" energy of normal polarity is supplied to the west end of line circuit K. The operation of this equipment is substantially the same as that associated with line circuit J and a detailed explanation of its operation is unnecessary.

Operation of equipment on movement of a train through the track stretch

For purposes of illustration it will be assumed that an eastbound train passes through the track stretch. When this train enters section 2T, track relay 2TR releases and interrupts the circuit of relay 3D so that its contacts 28 and 29 release and change the "master" code supplied to line circuit J from normal to reverse polarity. This causes the polar contacts of relay 5P to shift to their reverse positions so that contact 36 interrupts the circuit of the green lamp G and establishes the circuit of the yellow lamp Y of signal 5S. This will warn a westbound train of the approach of the eastbound train.

On this change in position of the contacts of relay 5P the connections from the line circuit to

relay 5N are changed so that even though the polarity of the energy supplied to the line circuit J is reversed, energy continues to flow in the same direction through the relay winding. Accordingly, the relay 5N continues to follow code so that energy is supplied through the decoding transformer 5DT to the relay 5H and to the impulse relay JIR. The relay JIR, therefore, continues to cause impulses of "feed-back" energy of normal polarity to be supplied to the line circuit J so that signal 4S continues to provide its green or clear indication.

As relay 5H remains picked up, the "feed-back" energy supplied to line circuit K continues to be of normal polarity and signal 7S continues to display its green or clear indication.

When the train advances into section 3T, track relay 3TR releases and its contact 25 interrupts the circuit for supplying energy of 180 code frequency to the coding relay JCR and establishes a circuit including back contact 47 of relay 3SR for supplying energy of 75 code frequency to the coding relay JCR. As a result, the contacts 26 and 27 of this relay operate at the lower frequency and "master" code energy of 75 code frequency is supplied to the line circuit J so that relay 5N follows this code and causes the relay JIR to supply "feed-back" energy to the line circuit to maintain the display of the clear indication by signal 4S.

When relay 5N is following energy of 75 code frequency, too little energy is supplied through the resonant unit 5RU to pick up the relay 5H. This relay, therefore, releases and its contact 35 establishes the circuit of the red or stop lamp R of signal 5S, while its contacts 48 and 49 cut off the supply of "feed-back" energy to line circuit K as contact 32 of relay 5SR is released. This causes relay 7H to release so that its contact 61 establishes the circuit of the red lamp R of signal 7S to thereby prevent a westbound train from advancing beyond signal 1S.

When the train advances into section 4T, track relay 4TR releases and its contacts 52 and 53 interrupt the line circuit J, and thereby prevent the supply of energy to line relays 4P and 4N, and also to relays 5P and 5N.

When the supply of "master" code to line circuit J is interrupted, relay 5N ceases to follow code and energy is no longer supplied to relay JIR so that this relay ceases to operate and impulses of "feed-back" energy are no longer supplied to the line circuit.

When the supply of "feed-back" energy to relays 4N and 4P is cut off by release of relay 4TR, relay 4H releases and its contact 44 establishes the circuit of the red or stop lamp R of signal 4S to warn a second or following eastbound train of the presence of the first train.

In addition, on release of the contacts 52 and 53 of track relay 4TR they short circuit the portion of the line circuit which is connected to line relays 4P and 4N during the released periods of the contacts 26 and 27 of coding relay JCR. As this portion of the line circuit is short circuited there is no possibility that the relay 4N will be energized if, because of a cross or other condition, energy is improperly supplied to this portion of the line circuit. The relay 4N, therefore, remains released and energy is not supplied through the transformer 4DT to relay 4H so that relay 4H will remain released and maintain the display of a stop indication by signal 4S.

On release of relay 4TR its contact 55 completes the circuit including back contact 56 of

relay 3TR for supplying energy to directional stick relay 3SR, and when the contacts of this relay pick up, its contact 51 establishes a circuit to maintain the relay energized as long as track relay 3TR is released. When the contacts of relay 3SR are picked up, its contact 47 interrupts the supply of energy of 75 code frequency to the coding relay JCR, while its contact 54 establishes the circuit to supply energy of 180 code frequency to this relay. The change in the rate of operation of relay JCR is without consequence, however, as long as section 4T or 5T is occupied since "master" code is prevented from being supplied over the line circuit when these sections are occupied.

When the train advances into section 5T, track relay 5TR releases and its contacts 58 and 59 interrupt and short circuit the line circuit J.

At this time "master" code energy of 180 code frequency and normal polarity continues to be supplied to the east end line circuit K so that signal 6S continues to provide its green or clear indication.

In addition, on release of relay 5TR its contact 53 releases, but because of the prior release of contact 62 of relay 5H the pick-up circuit of relay 5SR is not established and contact 63 of this relay remains released.

When the train enters section 6T, track relay 6TR releases and cuts off the supply of "master" code energy to relays 6P and 6N, while it also prevents the supply of "feed-back" energy to the line circuit K. In addition, on release of track relay 6TR its contacts short circuit the portion of line circuit K associated with line relays 1P and 1N to prevent improper energization of these relays as explained above.

Accordingly, relay 6N releases and energy is no longer supplied through the decoding transformer 6DT and the resonant unit 6RU to relay 6H, and this relay releases and its contact 64 establishes the circuit of the red lamp R of signal 6S.

The relay 6H is somewhat slow in releasing and its contacts remain picked up for a period subsequent to release of the contacts of relay 6TR. As a result on entrance of a train into section 6T, track relay 6TR releases and its contact 65 establishes a pick-up circuit for relay 6SR. This circuit includes front contact 80 of relay 6H. As soon as relay 6SR picks up, its contact 66 establishes a stick circuit for energizing the relay after release of relay 6H. When relay 6SR is picked up, its contact 67 permits supply of "feed-back" energy of reverse polarity to the line circuit J while relay 6H is released, while contact 68 of relay 6SR prevents the supply of "feed-back" energy to line circuit K.

When the train advances into section 7T, track relay 7TR releases and additionally interrupts and short circuits line circuit K.

When the train vacates section 3T, track relay 3TR picks up and its contact 56 interrupts the circuit of the relay 3SR so that this relay releases, while contact 25 of relay 3TR establishes a circuit to supply energy of 180 code frequency to the coding relay JCR.

In addition, when relay 3TR picks up, the circuit of the relay 3D is complete and the contacts 28 and 29 of this relay pick up so that the "master" code supplied to the line circuit J is again of 180 code frequency and normal relative polarity. When the train advances far enough to vacate sections 4T and 5T, line circuit J is again complete and the "master" code supplied to the line circuit feeds to the line relays 5P and 5N and

signal 5S is again conditioned to provide its green or clear indication.

As a result of code following operation of relay 5N, impulses of energy are supplied to relay JIR. At this time relay 6H is released, while, as explained above, relay 6SR is picked up. As long as section 6T is occupied, however, relay 6TR is released and its contact 39 prevents the supply of "feed-back" energy to line circuit J. Accordingly, signal 4S continues to display its red or stop indication when the train vacates section 5T.

When the train advances far enough to vacate section 6T, relay 6TR picks up and its contact 39 establishes the circuit for supplying impulses of "feed-back" energy of reverse polarity to line circuit J. At this time terminal B is connected through back contact 38 of relay 5SR, front contact 39 of relay 6TR, back contact 40 of relay 6H, and front contact 31 of coding relay JIR to line wire 21, while terminal C is connected through back contact 42 of relay 6H, front contact 67 of relay 6SR, and front contact 30 of relay JIR to line wire 20. As a result of the supply of "feed-back" energy of reverse polarity to line circuit J, the contacts of relay 4P are shifted to their right-hand or reverse positions, while energy is supplied through the decoding transformer 4DT to relay 4H so that its contact 44 picks up and cooperates with reverse polar contact 45 of relay 4N to light the yellow or caution lamp Y of signal 4S.

When the train advances into section 8T, track relay 8TR releases and interrupts the circuit of relay 8D so that its contacts 69 and 70 release and change the polarity of the "master" code energy supplied to line circuit K.

In addition, on release of track relay 8TR its contact 71 completes the pick-up circuit of relay 8SR. This circuit also includes back contact 72 of track relay 7TR, while, when relay 8SR picks up, its contact 73 establishes a stick circuit to maintain the relay energized as long as track relay 8TR is released.

On release of track relay 8TR its contact 74 interrupts one circuit for supplying energy of 180 code frequency to coding relay KCR, while contact 76 of relay 8SR establishes another circuit to supply energy of this code frequency to this relay. Accordingly, the coding relay KCR continues to operate at the 180 code rate.

In addition, on release of track relay 8TR the signal 8S is conditioned by means not shown to display its red or stop indication.

Similarly, when the train advances into section 9T, track relay 9TR releases and interrupts the circuit of relay 8D to maintain it released.

When the train advances far enough to vacate section 7T, track relay 7TR picks up and completes line circuit K so that "master" code of 180 code frequency and reverse polarity is supplied over the line circuit to the line relays 6P and 6N. The energy supplied to the line circuit is of reverse polarity as relay 8D is released and terminal B of the source is connected to line wire 23 through back contact 70 of relay 8D, while terminal C is connected to line wire 22 through back contact 69 of relay 8D.

The "master" code energy supplied to line circuit K causes the polar contacts of relay 6P to shift to their reverse positions, while relay 6N follows the code and energy is supplied through the decoding transformer 6DT and the resonant unit 6RU to pick up the relay 6H. Accordingly, the contact 64 of relay 6H interrupts the circuit of the red or stop lamp R of signal 6S, while it establishes a circuit including reverse polar con-

tact 77 of relay 6P to light the yellow or caution lamp Y of signal 6S.

In addition, on picking up of relay 6H its contact 80 interrupts the circuit of relay 6SR so that contact 68 of this relay releases and permits "feed-back" energy to be supplied to the line circuit K. At this time relay 5H is picked up as "master" code energy is supplied over the line circuit J so that the "feed-back" energy supplied to line circuit K is of normal polarity. The "feed-back" energy supplied to line circuit K energizes line relays 7N and 7P and these relays cause the green or clear lamp G of signal 7S to be lighted.

On picking up of relay 6H its contacts 40 and 42 change the "feed-back" energy supplied to line circuit J from reverse to normal polarity. On this change in the polarity of the "feed-back" energy supplied to line circuit J the polar contacts of relay 4P are shifted to their left-hand or normal positions and contact 45 establishes the circuit of the green or clear lamp G of signal 4S.

When the train advances far enough to vacate section 8T, track relay 8TR picks up and its contact 71 interrupts the circuit of relay 8SR, while its contact 74 establishes a circuit to maintain the supply of energy of 180 code frequency to coding relay KCR after release of contact 76 of relay 8SR.

When the train advances far enough to vacate section 9T, track relay 9TR picks up and completes the circuit of relay 8D so that the contacts of this relay pick up and change the "master" code supplied to line circuit K from reverse to normal polarity. On this change in the polarity of the "master" code supplied to line circuit K the polar contacts of relay 6P are shifted from their reverse to their normal positions and contact 77 establishes the circuit of the green lamp G of signal 6S. At this time there is no change in the polarity of the "feed-back" energy supplied to line circuits J and K so that signals 4S and 7S continue to display their green or clear indications.

The operation of the equipment on movement of a westbound train through the track stretch is substantially the same as for movement of an eastbound train through the track stretch and a detailed explanation thereof is unnecessary.

From the foregoing it will be seen that the invention is directed to use on single track stretches where for each direction of traffic there is one intermediate signal between adjacent passing sidings. The invention provides means requiring but a single line circuit to control the signal at the leaving end of a passing siding and governing traffic in one direction and to also control the intermediate signal governing traffic in the opposite direction.

It will be seen also that when the track stretch is vacant, "master" code energy of 180 code frequency and positive or normal polarity is supplied to each line circuit at the end thereof adjacent the headblock signal to control the intermediate signal, while "feed-back" energy of positive or normal polarity is supplied to the line circuit at the end thereof adjacent the intermediate signal to control the headblock signal.

When a train enters the overlap section at the leaving end of a passing siding, the "master" code supplied to the adjacent line circuit is changed from 180 code frequency to 75 code frequency. This energy is not effective to control the intermediate signal so this signal is caused to display its stop indication, but this energy causes "feed-

back" energy to be generated so that the head-block signal in front of the train continues to display its clear indication. In addition, on this change in the frequency of the "master" code the supply of the "feed-back" energy to the other line circuit is cut off to thereby cause the head-block signal at the leaving end of the adjacent passing siding in advance to display its stop indication.

When the train passes the headblock signal, the line circuit is interrupted and the headblock signal displays its stop indication. At this time "master" code of 180 code frequency continues to be supplied to the other line circuit to maintain the display of a clear indication by the intermediate signal in front of the train.

When the train passes the intermediate signal, the other line circuit is interrupted so that the intermediate signal is placed at stop. When the train vacates the stretch in the rear of the intermediate signal, "master" code of 180 frequency is again supplied over the line circuit associated with that signal and causes the intermediate signal for the opposite direction of traffic to again display its clear indication. The supply of "feed-back" energy to this line circuit continues to be cut off until the train vacates the track section in advance of the intermediate signal so that the headblock signal in the rear of the train continues to display its stop indication.

When the train does vacate the track section in advance of the intermediate signal, "feed-back" energy of reverse polarity is supplied to the line circuit in the rear of the intermediate signal so that the headblock signal in the rear of the train displays its caution indication.

When the train advances beyond the signal at the entrance end of the next passing siding and vacates the section in the rear of this signal, "master" code of 180 code frequency and reverse polarity is supplied over the line circuit to condition the intermediate signal in the rear of the train to display its caution signal, and to cause the "feed-back" energy supplied to the other line circuit to be changed from reverse to normal polarity and thereby cause the indication displayed by the headblock signal in the rear of that intermediate signal to be changed from caution to clear. In addition, at this time "feed-back" energy of normal polarity is supplied over the line circuit immediately in the rear of the train to condition the headblock signal in the rear of the train and controlling traffic in the opposite direction to display its green or clear indication.

Construction of modification shown in Fig. 2

In Fig. 2 of the drawings there is shown a modified form of signaling system which may be employed in place of that shown in Fig. 1. The system shown in Fig. 2 is similar to that shown in Fig. 1, but differs therefrom in that the code transmitters are located at the intermediate signal location instead of at the headblock signals. Accordingly, in the system shown in Fig. 2 "master" code is supplied from the intermediate signals to the headblock signals, while "feed-back" energy is supplied in the opposite direction.

The modification shown in Fig. 2, like that shown in Fig. 1, employs "master" code of two code frequencies, while the equipment at the headblock locations is arranged so that it will respond to only one of these frequencies to condition the associated signal to display a proceed

indication. However, "master" code of either frequency will cause "feed-back" energy to be developed and thereby cause the intermediate signal to display a proceed indication.

5 In the drawings showing the system of Fig. 2 most of the relay contacts are shown directly below the relay windings, but in some instances the contacts are shown separated from the windings. Where this is done, the relay with which the contact is associated is indicated by appropriate reference characters located directly above the contact.

10 The equipment of Fig. 2 is shown in the condition which it assumes when the track stretch is vacant. At this time the track relays are all picked up and line circuits J and K are both complete.

15 At this time energy of 180 code frequency is supplied to the coding relay JCR over the circuit which is traced from terminal B through the contact of code transmitter 180CT, front contact 100 of relay 6H, front contact 101 of track relay 6TR, and back contact 102 of relay 5SR. In like manner energy of 180 code frequency is supplied to coding relay KCR over the circuit which is traced from terminal B through the contact of code transmitter 180CT, front contact 105 of relay 5H, front contact 106 of track relay 5TR, and back contact 107 of relay 6SR. Accordingly, the coding relays JCR and KCR operate to supply 20 "master" code of 180 code frequency to the line circuits J and K.

25 As the relays 6H and 5H are picked up, the "master" codes are of normal polarity so that signals 4S and 1S are both conditioned to provide their green or clear indications.

30 As a result of code following operation of the relays 4N and JN, impulses of energy are supplied to the impulse relays JIR and KIR and these relays operate to cause impulses of "feed-back" energy to be supplied to the line circuits J and K. As the relays 3D and 8D are picked up, the "feed-back" energy is of normal polarity and signals 5S and 6S are conditioned to provide 35 their green or clear indications.

Operation of equipment on movement of an east-bound train through the track stretch.

40 When an eastbound train enters section 2T, track relay 2TR releases and interrupts the circuit of relay 3D so that relay 3D releases and changes the polarity of the "feed-back" energy supplied to line circuit J from normal to reverse. On this change in the polarity of the "feed-back" energy supplied to line circuit J the contacts of relay 5P are shifted to their reverse position and cause signal 5S to display its yellow or caution indication. At this time relay 5H remains picked up and "master" code of normal polarity continues to be supplied to line circuit K so that signal 1S continues to provide its green or clear indication.

45 When the train advances into section 3T, track relay 3TR releases and its contact 110 interrupts the circuit for supplying "feed-back" energy to line circuit J so that relay 5H releases and lights the red or stop lamp R of signal 5S. In addition, on release of relay 5H its contacts 111 and 112 change the polarity of the "master" code supplied to line circuit K from normal to reverse polarity, while as a result of the release of contact 105 of relay 5H the "master" code supplied to line circuit K is changed from 180 to 120 code frequency. The circuit for supplying energy to the coding relay KCR is traced from terminal

B through the contact of code transmitter 120CT, back contact 114 of relay 5SR, back contact 105 of relay 5H, front contact 106 of relay 5TR, and back contact 107 of relay 6SR.

On this change in the frequency of the "master" code supplied to line circuit K insufficient energy is supplied through the resonant unit 7RU to keep relay 7H picked up and this relay releases and causes signal 7S to display its red or stop indication to thereby prevent a westbound train from advancing beyond the passing siding Y.

The "master" code of 120 frequency supplied over line circuit K causes "feed-back" energy to be supplied to this line circuit. This energy is of normal polarity so that signal 6S continues to display its green or clear indication.

When the eastbound train is present in section 3T, "master" code of 180 code frequency continues to be supplied over the line circuit J to the line relays 4P and 4N so that relay 4H is picked up to maintain the display of a green or clear indication by the signal 4S.

When the train advances into section 4T, track relay 4TR releases and its contacts interrupt line circuit J to thereby cut off the supply of "master" code over this line circuit to the line relays 4P and 4J with the result that relay 4H releases and establishes the circuit of the red or stop lamp R of signal 4S.

In addition, on release of the track relay 4TR its contacts short circuit the portion of the line circuit J connected to the line relays 5P and 5N to prevent operation of these relays in the event energy is improperly supplied to the line circuit J.

When the train advances into section 5T, track relay 5TR releases and its contact 106 interrupts the circuit traced above for supplying energy of 120 code frequency to coding relay KCR and establishes another circuit for supplying energy of this frequency to relay KCR so that the supply of "master" code of 120 code frequency to line circuit K is maintained and "feed-back" energy continues to be supplied to the line circuit to maintain the display of a clear indication by signal 6S.

When the train advances into section 6T, track relay 6TR releases and interrupts line circuit K and thereby causes signals 7S and 6S to provide their red or stop indications.

At this time contact 115 of relay 6TR establishes the pick-up circuit for relay 6SR. This circuit also includes front contact 116 of relay 6H, while on picking up of relay 6SR its contact 117 establishes a stick circuit which includes back contact 116 of relay 6H.

When the train advances into section 7T, track relay 7TR releases and additionally interrupts line circuit K.

When the train vacates section 3T, track relay 3TR picks up and completes the circuit of relay 3D, while contact 110 of the relay 3TR establishes the circuit to permit "feed-back" energy to be supplied to line circuit J. However, "master" code is not supplied over the circuit at this time so that impulse relay JIR remains released and "feed-back" energy is not supplied to line circuit J.

When the train vacates sections 4T and 5T, the track relays 4TR and 5TR pick up and complete line circuit J to permit "master" code to be supplied over this circuit. At this time energy of 120 code frequency is supplied to coding relay JCR over the circuit which includes back contact 101

of relay 6TR, and back contact 102 of relay 5SR. Accordingly, the "master" code supplied to line circuit J is of 120 code frequency. This energy is ineffective to control signal 4S so that this signal continues to display its stop indication. This energy does produce operation of the impulse relay JIR so that "feed-back" energy is supplied to line circuit J. As relay 3D is picked up, the "feed-back" energy is of normal polarity and signal 5S is conditioned to display its green or clear indication.

When the train advances far enough to vacate section 6T, track relay 6TR picks up, but relay 6H remains released, while relay 6SR remains picked up by energy supplied over its stick circuit. On picking up of relay 6TR its contact 101 interrupts the circuit traced above for supplying energy of 120 code frequency to coding relay JCR, and establishes a circuit including front contact 119 of relay 6SR for supplying energy of 180 code frequency to coding relay JCR so that "master" code of 180 code frequency is supplied to the line circuit J. As relay 6H is released, this energy is of reverse polarity so that signal 4S is conditioned to provide its yellow or caution indication.

When the train advances into section 8T, track relay 8TR releases and interrupts the circuit of relay 8D, while contact 121 of relay 8TR completes the pick-up circuit of relay 8SR. This circuit also includes back contact 122 of relay 8TR, while when relay 8SR picks up its contact 123 establishes a stick circuit to keep the relay energized as long as relay 8TR is released.

In addition, on release of track relay 8TR the signal 8S is conditioned by means not shown to display its red or stop indication.

On release of relay 8TR its contact 125 interrupts one circuit for supplying "feed-back" energy to line circuit K, but on picking up of relay 8SR its contact 126 establishes another circuit to permit this energy to be supplied. Accordingly, when the train vacates section 7T and track relay 7TR picks up to complete line circuit K, "master" code is supplied over this line circuit so that impulses of energy are supplied to impulse relay KIR and this relay causes "feed-back" energy to be supplied to the line circuit. As relay 5H is picked up, the "master" code supplied to line circuit K is of normal polarity and conditions the signal 7S to display its green or clear indication, while as relay 8D is released, the "feed-back" energy supplied to line circuit K is of reverse polarity so that signal 6S displays its yellow or caution indication.

When the train vacates section 7T and feed-back energy is supplied over line circuit K so that relay 6H picks up, its contacts change the "master" code energy supplied to the east end of line circuit J from reverse to normal polarity. Accordingly, the contacts of relay 4P shift from their reverse to their normal positions and interrupt the circuit of the yellow lamp Y and establish the circuit of the green lamp G of signal 4S.

When the train advances far enough to vacate section 9T, the circuit of relay 8D is complete and this relay picks up to change the polarity of the "feed-back" energy supplied to line circuit K from reverse to normal to thereby condition signal 6S to provide its green or clear indication.

The operation of the equipment on movement of a westbound train is similar to its operation on movement of an eastbound train through the stretch and need not be traced in detail.

From the foregoing it will be seen that the modification shown in Fig. 2, like that shown in Fig. 1, provides means employing a single line circuit to control the signals for both directions of traffic in a track stretch. The modification shown in Fig. 2, like that shown in Fig. 1, employs "master" code in the line circuit to control the signals for one direction of traffic, and employs "feed-back" code in the same line circuit to control the signals for the other direction of traffic. The polarity of the "master" and "feed-back" energy is controlled to thereby provide two distinctive proceed indications for each direction of traffic.

In the system shown in Fig. 1 when a train enters the overlap section at the leaving end of a passing siding, the frequency of the "master" code is changed so that the intermediate signal governing traffic in the opposite direction is placed at stop, but "feed-back" energy is supplied to maintain the display of a proceed indication by the headblock signal in front of the train.

In the system shown in Fig. 2 the "master" code is supplied at the end of the line circuit adjacent the intermediate signal location. When a train enters the overlap section, "master" code continues to be supplied over the line circuit to maintain the display of a proceed indication by the headblock signal in front of the train, but the supply of "feed-back" energy over the line circuit is cut off to thereby place the intermediate signal for the other direction of traffic at stop.

In the system shown in Fig. 2 when the train advances into the track section in the rear of the intermediate signal, the frequency of the "master" code supplied to the line circuit in advance of the intermediate signal is changed. This causes the headblock signal at the leaving end of the passing siding in advance of the train to display a stop indication, but it also causes "feed-back" energy to be supplied to the line circuit to maintain the display of a proceed indication by the intermediate signal in front of the train.

Although we have herein shown and described only two forms of railway signaling system embodying our invention, it is understood that various changes and modifications may be made therein within the scope of the appended claims without departing from the spirit and scope of our invention.

Having thus described our invention, what we claim is:

1. In combination, a stretch of railroad track having a pair of track rails over which traffic moves in both directions, the rails of the track stretch being divided by insulated joints into a plurality of track sections including an intermediate section having at one side a first section and at the other side a second section, a first signal governing movement of traffic from the first section into the intermediate section, a second signal governing movement of traffic from the second section into the intermediate section, a line circuit substantially coextensive with and controlled by traffic conditions in said intermediate section, means governed by traffic conditions in said first section for supplying to the line circuit master code energy of a first or second code frequency and of one or the other polarity, means responsive to master code energy of either frequency and either polarity supplied over said line circuit for supplying feed-back energy to said line circuit, means responsive to master code energy of one code frequency only supplied over said line circuit and selectively responsive to the polarity

of such energy for controlling said second signal, and means responsive to feed-back energy supplied over said line circuit for controlling said first signal.

5 2. In combination, a stretch of railroad track having a pair of track rails over which traffic moves in both directions, the rails of the track stretch being divided by insulated joints into a plurality of track sections including an intermediate section having at one side a first section and at the other side a second section, a first signal governing movement of traffic from the first section into the intermediate section, a second signal governing movement of traffic from the second section into the intermediate section, a line circuit substantially coextensive with and controlled by traffic conditions in said intermediate section, means governed by traffic conditions in said first section for supplying to the line circuit master code energy of a first or a second code frequency and of one or the other polarity, means responsive to master code energy of either frequency and either polarity supplied over said line circuit for supplying feed-back energy to said line circuit, means governed by traffic conditions in said second section for controlling the polarity of the feed-back energy supplied to said line circuit, means responsive to master code energy of one code frequency only supplied over said line circuit and selectively responsive to the polarity of such energy for controlling said second signal, and means responsive to feed-back energy supplied over said line circuit and selectively responsive to the polarity of such energy for controlling said first signal.

3. In combination, a stretch of railroad track having a pair of track rails over which traffic moves in both directions, the rails of the track stretch being divided by insulated joints into a plurality of track sections including an intermediate section having at one side a first section and having at the other side a second section, a first signal governing movement of traffic from the first section into the intermediate section, a second signal governing movement of traffic from the second section into the intermediate section, a line circuit substantially coextensive with and controlled by traffic conditions in said intermediate section, means for supplying to said conductors master code energy of a first code frequency when said first section is vacant or is occupied by a train leaving said intermediate section and for supplying to said conductors master code energy of a second code frequency when said first section is occupied by a train advancing towards said intermediate section, means governed by occupancy of said first section and controlling the polarity of the master code energy supplied to said line circuit, means operated by master code energy of said first code frequency only and selectively responsive to the polarity of such energy for controlling said second signal, means responsive to the supply of master code energy of either frequency and either polarity for supplying feed-back energy to said line circuit, means governed by occupancy of said second section and controlling the polarity of the feed-back energy supplied to said line circuit, and means operated by feed-back energy supplied over said line circuit and selectively responsive to the polarity of such energy for controlling said first signal.

4. In combination, a stretch of railroad track having a pair of track rails over which traffic moves in both directions, the rails of said track stretch being divided by insulated joints into a

first, a second, a third and a fourth section, a first signal governing entrance of trains into the second section from the first section, a second signal governing entrance of trains into the second section from the third section, a line circuit substantially coextensive with and controlled by traffic conditions in said second section, means for supplying to said conductors master code energy of a first code frequency when said first section is vacant or is occupied by a train leaving said second section and for supplying to said line circuit master code energy of a second code frequency when said first section is occupied by a train advancing towards said second section, means governed by occupancy of said first section and controlling the polarity of the master code energy supplied to said line circuit, means operated by master code energy of said first code frequency only and selectively responsive to the polarity of such energy for controlling said second signal, means responsive to the supply of master

code energy of either frequency and either polarity over said line circuit and controlling a circuit over which feed-back energy may be supplied to said line circuit, means effective only when said third and fourth sections are vacant or are occupied by a train leaving said second section to permit feed-back energy to be supplied to said line circuit, means effective when said third section is vacant and said fourth section is vacant or is occupied by a train leaving said third section to cause the feed-back energy supplied to said line circuit to be of normal polarity, means effective when said third section is occupied by a train leaving said second section to cause the feed-back energy supplied to said line circuit to be of reverse polarity, and means operated by feed-back energy supplied over said line circuit and selectively responsive to the polarity of such energy for controlling said first signal.
